7 Claims. (Cl. 60—24)

1

This invention pertains to a hot-gas engine, and more particularly to a device for controlling the indicated power by modifying the phase angle between the working piston and the displacer piston.

It is known that by modifying the phase of the movements of the working piston and of the displacer piston, it is possible to regulate the course of the pressure in the cycle and consequently also the power of the motor. A known device for regulating this phase angle consists of separate drives for the piston and for the displacer, in which event the displacer is driven by two differently arranged eccentrics, which are connected with the rod of the displacer through the intermediary of a link beam, which construction is also found in piston steam engines which comprise a slide valve as the steam distributing member. Such a link construction has the drawback that the mass which is to be moved to and fro is large, which drawback is especially prevalent in engines running at a high speed.

A primary object of this invention is to overcome the above problem.

A further object of this invention is to provide means for altering the power output of a hot-gas engine.

A still further object of this invention is to provide a phase changer device for piston type engines.

Other objects and advantages of this invention will be apparent as the description proceeds hereinafter.

The drawing shows a preferred embodiment of the present invention.

According to the present invention, use is made of another distinctly different device from those mentioned and known for modifying the phase between the working piston and the displacer piston. Generally speaking, this device is characterized in that a separate crank shaft is present for the piston as well as for the displacer, which crank shafts are coupled with one another via gear wheels by means of an intermediate shaft which is slideable in the direction of the center-line of this shaft. Considering each of the gear wheels on the said intermediate shaft, it is noted that the quotient of the gear wheel diameter and the angle between the direction of the teeth and the center-line of the intermediate shaft is not equal to that of the other gear wheel, for if use is made of gear wheels with oblique or helical teeth there occurs simultaneously with the sliding movement of this intermediate shaft rotation of the latter. This rotation is equal to

2

the angular displacement of the point of application on the gear wheel of the gear wheel meshing therewith. The angle of displacement of this point of application is directly proportional to the angle which forms the teeth with the center-line of the intermediate shaft and is inversely proportional to the gear wheel diameter. If for the two gears on the intermediate shaft these quotients are equal, only the intermediate shaft is consequently rotated upon displacement, the shafts coupled therewith remaining at rest during this rotary motion. If the quotients are unequal, as in the case according to the invention, the angular displacement on the one gear wheel is consequently, with a determined displacement, not equal to that on the other gear wheel, and therefore the two crank shafts rotate relatively to one another and the phase angle between the two cranks varies.

20 A hot-gas engine is generally constructed in such manner that with a determined phase angle between the piston and the displacer, which angle may be, for example, 90°, the maximum indicated power is obtained. A larger phase angle is impossible from a constructional point of view because in this case the piston and the displacer would butt against one another; a smaller phase angle is, however, always possible. If the phase angle becomes zero, the indicated power is nil. 25 If the phase angle becomes negative, the motor rotates in the opposite direction. The negative value may rise to the same height as the maximum positive value, that is, 90°, as described hereinafter, so that it is again just impossible for the piston and the displacer to butt against one another. The device according to the invention is preferably constructed in such manner that the phase angle between the positive and negative maximum values is variable so that the described construction may serve not only for the control of the power but also for the reversal of the direction of rotation of the engine.

Owing to the fact that the displacer piston can be displaced with respect to the working piston, it is possible to start the engine by means of this construction.

The invention will be explained more fully with reference to the accompanying drawing, which represents, by way of example, one embodiment thereof.

The drawing represents only the parts of a hot-gas engine which are essential for an understanding of this invention. A working piston 11 and a displacer piston 10 being aligned piston means are connected to separate crank shafts 12

and 13 respectively through the intermediary of various cranks and connecting rods. Piston means 11 is coupled to the crank shaft 12 by a Y or wishbone shaped connecting rod means 11'. A piston rod 10' attached to the piston means 10 is coupled to the crankshaft 13 through the intermediary of offset pitman means 13'. The phase between the piston 11 and the displacer 10 consequently depends on the phase angle between the two crank shafts 12 and 13. Since a modification of this phase angle entails a change in the course of the pressure of the cycle, the indicated power of the engine may be varied by adjusting this phase angle.

These crank shafts are coupled with one another by means of an intermediate shaft 16 through the intermediary of screw wheels or gear means. Since in a hot-gas engine the speeds of the piston and of the displacer are equal, the ratio of transmission via this intermediate shaft and these gear wheels is 1:1. However, in order to be able to modify the indicated power, it must be possible to modify the phase angle relationship between the crankshafts 12 and 13. This is effected by displacing the intermediate shaft 16, which is coupled for this purpose with a lever 19. The intermediate shaft has mounted on it two screw or gear wheels or gear means 15 and 18 of which the former meshes with a gear wheel 14 on the crankshaft 12 and the latter with a gear wheel 17 on the crank shaft 13. The gear wheels 15 and 18 are constructed in such manner that upon displacement of the shaft 16 along its own axial length the shafts 12 and 13 perform unequal rotary motions so that the phase between these shafts varies. This consequently implies that upon displacement of the shaft 16 the point of application between the gear wheels 17 and 18 is displaced through another angle than the point of application between the gear wheels 14 and 15. With screw wheels or gears the displacement of the point of application or original contact depends on the pitch of the teeth and on the diameter of the gear wheel, and this in such manner that the angular displacement is greater according as the pitch angle is larger (by "pitch angle" is meant the angle formed between the teeth and the center-line of the shaft), this angular displacement being, with the same pitch angle, inversely proportional to the gear wheel diameter. Upon displacement in the direction of the shaft, gear wheels whose quotients of pitch angle and gear wheel diameter are equal may consequently undergo equal angle displacements, although the gear wheel diameters are unequal. In the case under consideration, however, the angular displacements may not be equal, so that the said quotients are consequently also unequal.

With a determined axial displacement of the intermediate shaft, a maximum variation of the phase angle between the crankshafts of the piston and of the displacer is obtained, if on the two gear wheels the angles formed between the teeth and the axis of the gear wheel are opposite. The numerical values of these quotients are therefore preferably made equal in order that two equal gear wheels milled in opposite directions may suffice. On the ground of these latter considerations the diameters of the gear wheels 15 and 18 and therefore also those of the gear wheels 14 and 17 are all made equal to one another.

What we claim is:

1. In a hot-gas engine, a device for controlling its indicated power by modifying the phase angle between its piston and displacer comprising a

crank shaft of the piston, a crank shaft of the displacer, parallel gear means fixed to each of said shafts, an intermediate shaft, gear wheels parallel with said gear means coupled to said intermediate shaft, said gear wheels being coupled to said gear means respectively, said gear wheels being so proportioned that the quotient of one gear wheel diameter and the angle between its teeth and center-line of the intermediate shaft is not equal to that of another gear wheel.

2. A device as claimed in claim 1 wherein said intermediate shaft is axially movable with respect to said crankshafts to such an extent that the phase angle varies from a positive maximum value to a negative maximum value.

3. A device as claimed in claim 1 wherein said quotients are of equal but of opposite values.

4. A phase changing device for a hot-gas engine comprising a piston crankshaft, a separate displacer crankshaft parallel to the first, gear means fixed to said shafts respectively, an intermediate shaft parallel to said shafts, spaced gear wheels coupled to said intermediate shaft, said gear wheels being so proportioned that the quotient of one gear wheel diameter and the angle between its teeth and the center-line of said intermediate shaft is not equal to that of another gear wheel whereby various longitudinal movements of the same into mesh with said respective crankshaft gear means cause phase angle differences between said crankshafts, and means for moving said intermediate shaft along its own longitudinal axis in two directions.

5. A phase changer device as claimed in claim 4 wherein said intermediate shaft is axially movable with respect to said two crankshafts to such an extent that said phase angles vary from positive values to negative values.

6. A device as described comprising aligned piston means, connecting rod means coupled to said means, a first one of said rod means being movable within one of said piston means, parallel crankshaft means coupled to said connecting rod means, offset pitman means, one of said crank shaft means being coupled to said offset pitman means, an intermediate shaft substantially interposed between said crankshaft means, gear wheel means fixed to said respective crankshaft means and intermediate shaft for coupling said piston means, and means for moving said intermediate shaft with gear wheel means thereon axially whereby the phase angle between said piston means is changed.

7. A device as claimed in claim 6 wherein the structural relationship of the gear wheel means on said intermediate shaft is such that the quotient of the gear wheel diameter and the angle of one gear wheel means between its teeth and center-line of said intermediate shaft is not equal to that of another gear wheel means.
